(57) **CLAIM**

The ornamental design for an alcohol distillation column apparatus as shown and described.

DESCRIPTION

FIG. 1 is a front view of the alcohol distillation column apparatus showing the design;

FIG. 2 is a top perspective view thereof;

FIG. 3 is a right side view thereof;

FIG. 4 is a left side view thereof;

FIG. 5 is a rear view thereof; and,

FIG. 6 is a top view thereof.

The broken lines in the drawings depict environmental structure and form no part of the claimed design and the bottom view is disclaimed.

1 Claim, 6 Drawing Sheets
